RECOVERY OF TAR ACIDS, ETC.

Stuart Parmelee Miller, Englewood, N. J., assignor to The Barrett Company, New York, N. Y., a corporation of New Jersey

Application September 26, 1931, Serial No. 565,270

6 Claims. (Cl. 183—114)

This invention relates to improvements in the recovery of tar acid oils and other products at coal distillation plants, particularly at coke oven plants.

5 In the ordinary operation of by-product coke ovens the gases produced by the coking operation pass from the individual ovens through uptake pipes and goose-necks to a collector main common to the ovens of the battery. The gases commonly known as foul gases leave the ovens at a high temperature, for example 600-700° C. or higher, and are ordinarily cooled as rapidly as possible by the application of sprays of ammonia liquor or ammonia liquor and tar in the goose-necks and collector main. The rapid cooling causes separation of a heavy tar in the collector main. Further cooling is effected in the cross-over main which connects the collector main to the condensing system where further cooling takes place and where tarry oils are separated from the gases. The heavy tar and tarry oils are commonly admixed with each other and subjected to distillation and the resulting distillate oils or selected fractions thereof are treated for the separation of tar acids or phenols therefrom.

10 The tars and tarry oils commonly recovered at by-product coke oven plants cannot be directly extracted to separate tar acids therefrom largely because of the tarry impurities which interfere with the action of the caustic solutions employed for the extraction and prevent satisfactory extraction from being effected. It is customary accordingly to ship the coal tar from a coke oven plant to a tar distillation plant there to be subjected to distillation and to treat the resulting distillate oils for the extraction of the tar acids. Handling losses, freight charges and distillation costs add materially to the cost of production of tar acid oils, tar acids and other tar distillation products, while the distillation in ordinary tar stills is accompanied with more or less decomposition and loss or change in tar acid constituents.

15 The improved process of the present invention eliminates the necessity of transportation of tar to a tar distillation plant and eliminates the necessity of distillation of the tar. It provides an improved method whereby tar acid oil can be recovered directly from the coke oven gases and tar acids can then be extracted from the oils and recovered at the coke oven plant.

20 According to the present invention the coal distillation gases from the coke ovens are subjected to a cleaning treatment while still at such a high temperature that the tar acids in the gases leaving the collector main are for the most part or

entirely maintained in a vapor state thereby removing from the hot gases all or substantially all suspended pitch constituents and leaving clean gases containing clean vapors. The cleaning of the gases at a high temperature is effected by passing the gases through an electrical precipitator at a regulated speed and subjecting the gases to an electrical discharge of sufficient intensity to effect substantially complete cleaning of the gases. Pitch constituents carried in the gases are removed in the precipitator and drawn off as a separate pitch product and the tar acid vapors remain admixed with the clean gases and other clean vapors issuing from the precipitator. The clean gases are then cooled to separate therefrom a clean oil rich in tar acids from which the tar acids are extracted directly. The gases are subsequently treated for the recovery of ammonia, benzol and other light oils therefrom. No tar is produced according to this process, the pitch constituents entrained in the gases being removed as pitch, while the gases are still hot.

25 Archibald F. Meston in U. S. Patent No. 1,444,627, issued February 6, 1923, describes a method of detarring coke oven or retort gases in an electrical precipitator and then removing ammonia and benzol from the gases. He provides two precipitators and a cooling chamber for cleaning the gases. Part of the tar is removed from the gases in one precipitator and then, after cooling, all such tar particles as may have escaped the action of the first precipitator and have been subsequently condensed by cooling are removed from the gases in the second precipitator. The cleaning process in the Meston process is not completed until after the gases have been cooled below the dewpoint of the gases for water. The clean gases are treated for the removal of ammonia and benzol. The present invention may be considered in the nature of an improvement over the Meston process in so far as it provides for cleaning the gases, while hot, to such an extent that on cooling there is obtained a tar acid oil of sufficient purity to permit extraction of the tar acids directly with an alkaline reagent.

30 In ordinary coke oven systems the gases are cooled in the collector main by the introduction of ammonia liquor or ammonia liquor and tar therein, and heavy tar is thrown out of the gases in this main. Some of the tar acids may be thrown down from the gases with the heavy tar separated in the collector main. The present invention contemplates regulated cooling of the gases in the collector main. By keeping the temperature of the gases escaping from the main

55

sufficiently high the greater part of the tar acids will be carried over in vapor form from the collector main to the electrical precipitator.

The temperature at which the gases are subjected to cleaning may be varied depending upon whether only lower tar acids are desired or whether higher tar acids are also desired. Even at temperatures around 90° C. a considerable amount of the lower boiling tar acids are retained 10 in the vapor state in normal coke oven gases and if the gases are cleaned at this temperature and then cooled, the oil which is obtained will contain substantial amounts of tar acids, particularly phenol and the cresols. A higher yield of tar acids including most of the lower boiling tar acids 15 is obtained by cleaning the gases at a somewhat higher temperature, around 100 or 110° C., for example. Cleaning at 120° C. gives a high yield of tar acid oils. By cleaning the gases at a temperature 20 around 150° C. most, if not all, of the tar acids in the gases will be retained as vapors and on subsequent cooling a tar acid oil containing substantially all of the tar acids will be obtained in admixture with a large percentage of 25 non-acid or neutral oils. The temperature at which the gases are cleaned can be regulated and varied to obtain a larger or smaller yield of the tar acids as tar acid oils. By fractional cooling, two or more separate tar acid oils may be 30 obtained suitable for the extraction of separate tar acid fractions. For example, by cooling the cleaned gases first to a temperature above the dew point of the gases for water, collecting the condensed oils, and then cooling to a temperature 35 below, say 35° C., two tar-acid oils may be condensed, the lower one yielding tar acids rich in the commercially valuable cresols and phenols.

After the gases have been subjected to cleaning 40 in the electrical precipitator they will contain the tar acids in the form of vapors together with non-acid or neutral oils also in the form of vapors and the gases will be substantially free from suspended pitch impurities. The substantially complete removal of suspended particles from the 45 gases at a temperature above the dew point of the tar acids which are to be recovered and production of a commercially clean oil are essential features of the invention because the presence of any substantial amount of pitch constituents in 50 the tar-acid oils presents difficulties during the extraction with an alkaline reagent and makes the direct recovery of tar acids from such oils difficult and expensive on a commercial scale. Free carbon is an easily determinable pitch 55 constituent and is commonly used as a measure of the suitability of a tar acid oil for extraction. Since the free carbon content is not the sole factor governing emulsion formation during extraction, there will be some variation under different 60 conditions and with different oils of the permissible free-carbon content of the oil. Ordinarily a free-carbon content of not over 0.2% is desirable, but as much as 0.5% may be permissible under special circumstances.

65 By "free carbon" is meant benzol-insoluble material determined as described by Weiss for tar in the Journal of Industrial and Engineering Chemistry, Vol. 10 (1918), p. 736, with such modification as is necessary for applying to oil, *ibid.* p. 911.

In recovering the tar acids from the cleaned gases, the gases should, in general, be cooled to a temperature around 25-30° C. in order to separate as much of the oils containing tar acids as possible. This cooling can be effected by indi-

rect cooling or by direct cooling and is advantageously effected by introducing a spray of water or ammonia liquor into the gases so that they are rapidly cooled to around 25-30° C. The gases at this lower temperature may be again subjected to the action of an electrical precipitator to effect substantially complete removal therefrom of all suspended liquid constituents, thereby insuring that the maximum amount of condensed oils will be obtained, and leaving the gases substantially free from such suspended oil.

The gases from which the tar acid oils have been removed will still contain large amounts of ammonia, although some of the ammonia will have been removed therefrom in the condensers, 15 in which the tar acid oils have been removed, particularly where a direct water or ammonia liquor spray is employed for cooling the gases to separate the tar acid oils. The gases after cooling to separate the tar acid oils can be passed 20 directly to a saturator or absorber for the absorption of ammonia in sulfuric acid but they may advantageously be reheated somewhat to a temperature around 55° C., for example, before being passed to the absorber. The gases leaving 25 the absorber are cooled and are then subjected to scrubbing with a suitable solvent for the recovery of light oil, such as benzol, etc., therefrom. The benzol recovered in this manner will be free 30 from tarry constituents present in gases which have not been subjected to a prior cleaning operation.

The improved process of the present invention can be carried out with existing equipment by the provision of an electrical precipitator at the 35 exit of the gases from the collector main and by regulation of the temperature of the gases entering and leaving the collector main. The electrical precipitator will be constructed so as to be capable of withstanding the high temperatures to 40 which it is subjected in the operation as described and it will be so constructed and operated as to effect the removal of substantially all suspended particles from the gases while they are still at a high temperature and before the condensation of the tar acid oils therefrom. The precipitator may advantageously be insulated to 45 prevent loss of heat during the cleaning operation.

To subject the gases to uniform treatment and 50 effect the thorough removal of suspended particles contemplated by this invention, the gases are passed between the electrodes of the precipitator at a regulated rate while being subjected to an electrical discharge of regulated high potential. The efficiency of the cleaning operation is a function of the time during which the gases are subjected to the electrical discharge, i. e., the actual length of time the gas is in the electrical field.

The invention will be further illustrated by the 55 following more detailed description in connection with the accompanying drawings, which show apparatus embodying the invention.

Fig. 1 is a plan view of a portion of a coke oven 60 plant illustrating the application of the invention thereto;

Fig. 2 is an enlarged sectional view of the electrical precipitator and collector main;

Fig. 2A is a sectional elevation of the precipitator; and

Fig. 3 is an enlarged sectional view of the tar acid extraction apparatus.

Referring to the drawings, 5 indicates a battery of coke ovens the individual ovens of which 75

are connected by uptake pipes and goose-necks 6 to a collector main 7 having a center box 8. Ammonia liquor or other aqueous cooling agent, or tar and ammonia liquor, can be supplied to the goose-neck and collector main through spray nozzles 9 and 9' therein which are supplied by a pipe 10 from a suitable source of the cooling liquid. As hereinbefore indicated, the amount of ammonia liquor thus supplied may be regulated so that the temperature of the gases leaving the collector main is, for example, not lower than 100° C. and in many cases higher so that the gases will carry from the collector main a considerable proportion of the oil constituents containing tar acids. The tar or pitch and ammonia liquor which accumulate in the center box can be withdrawn through a pipe 11 to a decanter 12 wherein the tar or pitch is separated from the ammonia liquor. The tar and ammonia liquor can be utilized for any desired purpose. For example, the tar or pitch can be distilled to separate additional quantities of oil therefrom and to produce pitch adapted for various commercial purposes.

25 The gases and vapor leaving the collector main are conducted directly through a pipe 14 to an electrical precipitator 15 which is arranged preferably closely adjacent to or upon the collector main in order that the temperature of the gases may not be reduced to any considerable extent before the separation of suspended pitch impurities from the gases. The electrical precipitator consists of a shell enclosing a number of tubes 15' supported in heads 16 and 17 within the shell. An inlet 18 near the bottom of the shell communicates with a chamber 19 which is partially separated from the tube section by a baffle 20. An outlet 21 permits the escape of the gases from the separator after the latter have passed through the tubes.

40 Extending through each tube is a metal rod 22 which is supported from a bus-bar 23 located near the upper end of the tubes. The bus-bar 23 extends at both ends into casing 24 which encloses insulators 25 upon which the bus-bar is supported. The high tension current line extends into one of the casings 24 and connects with the bus-bar 23. The current is ordinarily obtained by the stepping-up and rectification of an alternating current of lower voltage.

50 The casing of the precipitator is grounded or otherwise connected to the source of current to complete the circuit. The casing and tubes form the positive electrode, the rods 22 connected to the bus-bar being the negative electrode. The form and arrangement of the conductors in the circuit can be varied.

55 The size and number of tubes in the precipitator is such that the gases in passing through the tubes remain in the tubes and are subjected to the electrical discharge therein for a period of about one second or more in order to effect the substantially complete removal of suspended particles required for the preparation of tar acid oils. Tubes about nine feet long and six inches in diameter are preferred. Tubes of greater length may be employed and in employing tubes of such greater length the rate at which the gases are passed through the tubes may be increased in proportion to the increase in length of the tubes, but tubes longer than nine feet are not ordinarily desirable due to the difficulty of maintaining the discharge electrode in the center of such longer tubes. Tubes of shorter length may be employed and in this case the speed of the

gases should be decreased proportionately. Owing to the slowing up of the process by the use of such shorter tubes, longer tubes are generally preferred. Tubes around nine feet long will generally be employed.

5 To maintain the cleaning efficiency of the precipitator at the uniformly high standard required for producing the clean tar acid oils of this invention it is very necessary to keep the secondary voltage of the precipitator, i. e. the 10 voltage between the discharge and collecting electrodes at very nearly the "break down" voltage, i. e. the voltage which produces sparking between the electrodes. Using collecting electrodes six inches in diameter this break down voltage 15 is approximately 50,000 volts but will vary somewhat depending upon several factors, among which are the amount of suspended matter in the gases being cleaned and the condition of the inside walls of the collecting electrodes.

20 The use of tubes of maximum diameter is desirable to obtain maximum cleaning capacity with the greatest simplicity of construction. The practical limit at present is largely determined by the maximum voltage that can be used without undue losses or other disadvantages. Tubes of 25 6 inches internal diameter have been found in practice to meet operating conditions satisfactorily in this respect, and are the preferred size in this process.

30 If deposits of pitch build up on the inside walls of the tubes so as to permit a concentration of surface charge at any one point, a spark discharge will take place between the discharge electrode and the tube. When this occurs the 35 cleaning efficiency drops to practically zero. A voltage somewhat under the break down voltage is maintained between the electrodes and in cleaning gases in six inch tubes a voltage of about 45,000 to 47,000 volts will ordinarily be maintained between the electrodes. Voltages as low as 40,000 volts may be employed in some cases but when the break down voltage falls below about 40,000 volts the precipitator must be cleaned.

45 Larger tubes require higher voltages, for example about 75,000 volts for ten inch tubes and 325,000 volts for thirty-six inch tubes.

50 With tubes of the preferred length, i. e. nine feet, the rate of flow of the gases through the 55 tubes is preferably not greater than nine feet per second, the gases thus being subjected to cleaning for approximately one second. This rate of flow should be maintained regardless of the diameter of the tubes. The velocity of the gases may be somewhat less than nine feet per second, but in order to operate most efficiently the precipitator will be designed so that a velocity of eight or nine feet per second will be maintained in treating ordinary coke oven gases in tubes nine 60 feet long. In any case a maximum velocity of ten or even eleven feet per second should usually not be exceeded. The content of suspended matter in the gases is at least to some extent dependent upon the temperature of the gases, so that 65 the time of treatment may vary somewhat with the temperature at which the gases are cleaned.

Since the rate of flow of gases from the coke oven plant is subject to variation due to changes in the coking cycle and changes in the temperature of the gases treated, a precipitator should be designed to maintain the desired efficiency of cleaning under peak conditions.

70 The hot gases from the collector main, carrying pitch in the form of globules or "tar fog", 75

enter the electrical precipitator and pass through the tubes in the precipitator, being subjected therein to the electrical discharge which causes the suspended particles to separate from the 5 gases and condensable vapors. The pitch is thus thrown out of the gases and runs down the inner walls of the tubes into the chamber 18 and is withdrawn from the bottom of the precipitator through the outlet 25'.
 10 The cleaned gases carrying the condensable vapors escape through the outlet 21 to a cross-over main 26 and are delivered thereby to condensers 27. The condensers may be of any suitable form, for example, the ordinary direct or "wet" type which is employed frequently in by-product recovery systems. The gases and vapors are cooled therein by contact with grid surfaces wet by sprays of ammonia liquor, for example, to a temperature of 25° C. or 35° C., and the resulting condensate is withdrawn through pipes 27' to a decanter 28 wherein the oil is separated from the ammonia liquor. The gases pass from the condensers through a pipe 29 to an exhauster 30. The gases are then conducted, with or without reheating, to an ammonia absorber or saturator 31 to recover ammonia therefrom and thereafter to suitable apparatus (not shown) for the recovery of light oils, etc.
 15 The oil separated in the decanter 28 can be conducted to tanks 32' and thence through a pipe 32 to extraction apparatus 33 which may comprise a tank having suitable agitating means 34 therein. The extraction agent, for example, caustic alkali, can be added in suitable proportions to the tank through an inlet 35 and mingled with the oil by agitation until the extraction is accomplished. The agitation can then be discontinued. The carbolate will settle to the bottom of the tank, providing caustic soda solution of 10% or higher 20 strength is used. After sufficient settling the carbolate is drawn off through pipe 36. The line of demarcation between the carbolate and the oil is sufficiently distinct to allow a close separation to be made. When the carbolate has been completely removed, the extracted oil is removed to storage. The separation is easily conducted if a sight box 37 is used. The carbolate can be treated in the ordinary manner for removal of dissolved 25 oils and liberation and recovery of tar acids.
 20 The removal of pitch from the gases in the precipitator must be complete or so nearly complete that the oils obtained by cooling the resulting gases can be extracted directly for tar acids. The presence of any considerable amount of pitch or 30 tarry constituents in the oils will cause the formation of emulsions when treated with caustic. This invention contemplates the production of clean oils which can be extracted directly.
 35 The relation of cleaning efficiency to time of treatment of the gases in the precipitator for a given set of operating conditions is shown in the following table:

Time of treatment in seconds	Percentage of suspended matter removed
0.46	73.7
.58	80.0
.69	86.8
.93	93.4
1.05	95.2
1.40	98.1

Unless the time of treatment is approximately 75 one second, the cleaning effected in the precipi-

tator is not adequate to produce a tar acid oil which can be extracted directly for tar acids without formation of troublesome emulsions.

For example, the gases from a battery of twenty coke ovens, each charged with thirteen tons of coal, operating on a coking cycle of nineteen hours and therefore coking 329 tons of coal each twenty-four hours, can be cleaned at 100° C. in a precipitator containing 63 tubes, six inches in diameter and nine feet long, by maintaining a voltage of 10 45,000 to 47,000 volts between the electrodes. If the gases are treated at an appreciably higher temperature a larger number of tubes is required owing to the larger volume of hotter gases.

An installation for twenty ovens using nine feet 15 tubes six inches in diameter should include somewhat more than 63 tubes to allow for variations in the length of the coking cycle, the different temperatures at which the gases may be treated and other changes in operating conditions, and 20 those tubes which are not needed may be blocked off by suitable means known in the art.

According to a preferred method of carrying out the process, the gases are cleaned at a temperature of 110° C. At this temperature pitch 25 melting at about 110° F. (cube in water method) will be thrown down in the precipitator and by cooling the cleaned gases to 30° C. an oil yield of approximately 20% of the tar will be obtained. If the gases are cleaned at 100° a pitch with a 30 float test of approximately 50-160 seconds at 50° C. (A. S. T. M. 139-27) will be obtained and a somewhat lower oil yield will result, but the phenol content of the oil will be relatively somewhat higher and the content of higher boiling tar acids 35 will be relatively somewhat lower than if the gases are cleaned at 110° C.

After cooling the gases to throw down the tar acid oil, it is desirable to reheat the gases to 50-55° C. before recovering the ammonia by the 40 direct method of absorption in sulfuric acid. While various methods for the recovery of ammonia may be employed, the removal of ammonia by direct contact with sulfuric acid will ordinarily be preferred.

The extraction of the clean, directly recovered tar acid oil for the separation of tar acids therefrom can be effected in apparatus of the kind commonly used for extracting tar acids from distillate oils, using an aqueous solution of caustic soda or sodium sulfide or other phenol absorbing reagent and bringing about intimate contact of the oil with the caustic alkali solution to cause the tar acids to combine with the caustic alkali, etc. A solution containing about ten percent of caustic soda can advantageously be employed for the extraction of the tar acids, although a stronger or weaker solution may be employed. The solution, when brought into intimate contact with the oil extracts the tar acids therefrom and forms a phenolate or carbolate solution containing the alkali salts of the tar acids. This solution can be separated from the extracted neutral oils which are thus obtained substantially free from tar acids and the solution can then be treated to recover the tar acids therefrom.

The treatment of the phenolate solution may be preceded by evaporation or distillation to drive off volatile oil constituents such as pyridine bases, etc. therefrom. It can then be treated with an acid, such as carbon dioxide, to set free the phenols or tar acids in a separate layer, which can then be separated and subjected to further treatment by distillation or refining to obtain commercial tar acid products. In this way individ-

ual phenols, or commercial mixtures of phenols, can be obtained, e. g., cresols, cresylic acid, etc.

The neutral oils remaining after the extraction of the tar may be further fractionated, if desired, to recover therefrom oils having different boiling points and adapted for various uses. The neutral oil is a valuable oil for use in lamp-black manufacture. It may be converted to lamp-black by incomplete combustion. The oil, particularly heavier fractions thereof, can also be advantageously employed in creosoting compositions.

This application is in part a continuation of my application Serial No. 202,736; filed June 30, 1927.

I claim:

1. The method of recovering from hot coal distillation gases a tar acid oil, which comprises cooling the gases to a regulated temperature at which tar acids are retained in vapor phase but below that at which the oils remaining in the gases in vapor phase constitute a creosote oil, subjecting the gases to cleaning to remove substantially all suspended matter therefrom, and cooling the resultant clean gases to separate therefrom a tar acid oil substantially free from tarry constituents.

2. The method of recovering a tar acid oil from hot coal distillation gases, which comprises cooling the gases to a temperature above their dew point for water and below about 150° C., cleaning the gases at this temperature to remove suspended matter therefrom, and cooling the resultant clean gases to separate therefrom a tar acid oil substantially free from pitch constituents.

3. The method of recovering a tar acid oil from hot coal distillation gases, which comprises cooling the gases to a temperature above their dew point for water and below about 150° C., cleaning

the gases at this temperature to remove suspended matter therefrom, and cooling the resultant clean gases to separate therefrom a tar acid oil containing not more than about .5% free carbon.

4. The method of recovering from hot coal distillation gases a tar acid oil, which comprises cleaning the gases by electrical precipitation while yet at a temperature above their dew point for water and below about 150° C. to remove suspended matter therefrom, and cooling the resultant clean gases to separate therefrom a tar acid oil substantially free from pitch constituents.

5. The method of recovering from hot coal distillation gases a tar acid oil readily extractable with aqueous caustic soda for removal of tar acids therefrom, which comprises cleaning the gases by electrical precipitation while yet at a temperature above their dew point for water and below about 150° C. to remove suspended matter from the gases and leave in the gases not more than .5% of free carbon based on the weight of oil vapors retained in the gases, and cooling the resultant clean gases to separate therefrom a caustic extractable tar acid oil containing not more than about .5% of free carbon.

6. The method of recovering from hot coal distillation gases a tar acid oil readily extractable with aqueous caustic soda for removal of tar acids therefrom, which comprises cleaning the gases by electrical precipitation while yet at a temperature above their dew point for water and below about 150° C. to remove suspended matter from the gases and leave in the gases not more than .5% of free carbon based on the weight of oil vapors retained in the gases, and cooling the resultant clean gases to a temperature below about 35° C. to separate therefrom a caustic extractable tar acid oil containing not more than about .5% of free carbon.

S. P. MILLER. 40
